UNITED STATES PATENT OFFICE.

JOHN GILSON, OF PORT WASHINGTON, WISCONSIN, ASSIGNOR TO GILSON MANUFACTURING COMPANY, OF PORT WASHINGTON, WISCONSIN.

SPRING-BACK CHAIR.

SPECIFICATION forming part of Letters Patent No. 758,133, dated April 26, 1904.

Application filed February 20, 1904. Serial No. 194,475. (No model.)

To all whom it may concern:

Be it known that I, JOHN GILSON, a citizen of the United States, and a resident of Port Washington, in the county of Ozaukee and State of Wisconsin, have invented certain new and useful Improvements in Spring-Back Chairs; and I do hereby declare that the following is a full, clear, and exact description thereof.

My invention consists in certain peculiarities of construction and combination of parts hereinafter particularly set forth, with reference to the accompanying drawings, and subsequently claimed, the object of said invention being to simplify and cheapen the manufacture of spring-back chairs, as well as to provide an antibinding noiseless coupling for the back and seat of such a chair.

Figure 1 of the drawings represents a vertical section view of a chair-seat spider and a spring-back coupling in accordance with my invention applied in connection with an arm of said spider; Fig. 2, a plan view of what is shown in Fig. 1, a recurved yielding strap constituting part of the coupling being partly broken away; Fig. 3, a transverse sectional view indicated by line 3-3 in Fig. 1, and Fig. 4 a perspective view of a plate constituting part of said coupling.

Referring by letter to the drawings, A indicates the rear arm of what is ordinarily a chair-seat spider, and B an adjusting-screw made fast at its upper end in the spider. Said arm of the spider is shown made partly open to economize metal, and the outer portion thereof is virtually a plate from which a rear guard-flange *b* depends.

Preferably riveted or otherwise rigidly secured to the under side of the spider-arm A, adjacent to the flange *b* of same, is one end of a recurved spring-steel strap C, and the bend *c* of this strap is made to depend below the under stretch of same. Opposite inner lateral lugs *d* of said spider-arm serve as forward supports for the strap C, and countersunk in the solid portion of the arm is the partly-squared head of a bolt D, that extends through the upper stretch of said strap and a plate E, a bur *e* of this plate being engaged with an aperture in the under stretch of the

strap. This under stretch of the strap is flanked by upwardly-extending lugs *f* of the plate E and caught under a raised bar *g* of said plate. The bar connects a pair of rearwardly-extending side lugs *h* of the plate E, and forward depending curved fingers *i* of said plate bear upon the depending bend *c* of the aforesaid strap. Each lug *h* of the plate E is bored longitudinally thereof to receive the lower horizontal end of a suitably-bent spring-rod F, that constitutes part of a chair-back, and a set-screw *j* may be employed in connection with said lug to bind said rod in engagement therewith.

Surrounding the bolt D, between the plate E and a washer *k*, is a spiral spring G of suitable strength, and the tension of this spring is regulated by adjustment of a nut H, run on said bolt, against said washer.

In practice the yield of the chair-back is against resistance of its rods F and the spring G, the recurved yielding strap C serving to prevent binding and noise in the joint between said chair-back and seat-spider or a seat attachment virtually the same as the rear arm of said spider.

Having thus described my invention, what I claim as new, and desire to secure by Letters Patent, is—

1. A chair-seat attachment, a recurved spring-metal strap supported by the attachment, a chair-back-supporting plate hung on the under stretch of the strap, a bolt extending through said attachment, strap and plate; a plate-opposing spring, and a nut adjustable on the bolt to regulate tension of the spring. 75

2. A chair-seat attachment, a recurved spring-metal strap supported by the attachment, the bend of the strap being partly below the under stretch of same, a chair-back-supporting plate hung on the under stretch of the strap and extended parallel to the bend aforesaid, a bolt extending through said attachment, strap and plate; a plate-opposing spring, and a nut adjustable on the bolt to regulate tension of the spring. 85

3. A chair-seat attachment, a recurved spring-metal strap supported by the attachment, the bend of the strap being partly be-

low the under stretch of same, a chair-back-supporting plate hung in connection with said under stretch of the strap and extended parallel to the bend aforesaid, strap-opposing lugs on the plate, a bolt extending through said attachment, strap and plate; a plate-opposing spring, and a nut adjustable on the bolt to regulate tension of the spring.

4. A chair-seat attachment, a recurved spring-metal strap supported by the attachment, the bend of the strap being partly below the under stretch of same, a plate having rearwardly-extended and bored side lugs connected by a bar under which the lower end of said strap is caught, said plate being extended parallel to the bend aforesaid, a bolt extending through said attachment, strap and plate; a plate-opposing spring, and a nut adjustable on the bolt to regulate tension of the spring.
5. A chair-seat attachment having opposite inner lugs, a recurved spring-metal strap supported on said lugs, a chair-back-supporting plate hung on said under stretch of the strap, a bolt extending through said attachment, strap and plate; a plate-opposing spring, and a nut

adjustable on the bolt to regulate tension of the spring.

6. A chair-seat spider having the rear arm thereof partly in the form of a plate and provided with inner opposite lateral lugs, a re-curved spring-metal strap supported on the lugs and made fast at one end to said plate portion of the spider-arm, the bend of the strap being partly below the under stretch of same; a plate having rearwardly-extending and bored side lugs connected by a bar over the other end of said strap, said plate being extended parallel to the bend aforesaid; a bolt extending through said spider-arm, strap and plate; a plate-opposing spring, and a nut adjustable on the bolt to regulate tension of the spring.

In testimony that I claim the foregoing I have hereunto set my hand, at Port Washington, in the county of Ozaukee and State of Wisconsin, in the presence of two witnesses. 45

JOHN GILSON.
